UNITED STATES PATENT OFFICE

163,983

REFRIGERATOR

Raymond A. Wyatt, Detroit, Mich.

Application March 5, 1951, Serial No. 14,382

Term of patent 7 years

(Cl. D67—3)

To all whom it may concern:

Be it known that I, Raymond A. Wyatt, a citizen of the United States of America, residing at Detroit, in the county of Wayne, and State of Michigan, have invented a new, original, and ornamental Design for a Refrigerator, of which the following is a specification, reference being had to the accompanying drawing, forming part thereof.

Fig. 1 is a perspective view from the front and one side of a refrigerator showing my new design;

Fig. 2 is a side elevation taken from the left side of Fig. 1; and

Fig. 3 is a plan view.

I claim:

The ornamental design for a refrigerator, as shown.

RAYMOND A. WYATT.
